DESIGN FOR A MOP WRINGER

Irwin Siebert, Cleveland, Ohio

Application September 30, 1943, Serial No. 111,239

Term of patent 14 years

(Cl. D49—1)

To all whom it may concern:

Be it known that I, Irwin Siebert, a citizen of the United States, residing at Cleveland, in the county of Cuyahoga and State of Ohio, have invented a new, original, and ornamental Design for Mop Wringers, of which the following is a specification, reference being had to the accompanying drawing, forming part thereof.

I claim:

The ornamental design for a mop wringer, as shown.

IRWIN SIEBERT.
